E. B. HESS

TYPEWRITING MACHINE

Filed May 3, 1924

UNITED STATES PATENT OFFICE.

EDWARD B. HESS, OF NEW YORK, N. Y., ASSIGNOR TO ROYAL TYPEWRITER COMPANY, INC., OF NEW YORK, N. Y., A CORPORATION OF NEW YORK.

TYPEWRITING MACHINE.

Application filed May 3, 1924. Serial No. 710,797.

To all whom it may concern:

Be it known that I, EDWARD B. HESS, a citizen of the United States, residing at New York, in the county and State of New York, 5 have invented certain new and useful Improvements in Typewriting Machines, of which the following is a specification.

This invention relates to the paper feeding and guiding mechanism of typewriting machines. In the Royal Standard machine as heretofore marketed, the paper is fed under the platen and held in yielding contact therewith by a group of rolls mounted in frames which can be adjusted to withdraw 10 the rolls from the platen when it is desired to arrange the paper upon the platen. These combined feeding, guiding, and pressure rolls cooperate with pressure rolls which normally hold the paper, after passing 15 around the front of the platen, with a yielding pressure on the upper portion of the platen. Means have heretofore been provided, and as shown in prior patents issued to the Royal Typewriter Company, Inc., for 20 so moving these upper pressure and guiding rolls that they may be changed from their normal or working position on top of the platen to a position above and in rear of the platen and in rear of the paper table. In 25 the Royal Standard machine, the top pressure rolls are mounted on a horizontally arranged rod extending from one end of the platen to the other and beyond the ends thereof, and this rod is mounted in what is 30 known as a bail comprising side arms or members which are pivotally connected with the carriage frame in rear of the platen and a considerable distance therefrom. These side arms of the bail are braced by a rod 35 which extends from one side arm to the other, and springs are employed for holding the rolls on the platen. While normally the bail holds the pressure rolls yieldingly and with equal pressure upon the platen, it sometimes happens that in a careless use of the 40 machine the bail is bent or misshaped so that a pressure roll on one side of the machine bears with greater pressure on the platen than the roll on the opposite side 45 thereof. It is the object of my present invention to remedy this difficulty in such manner that even though the bail be bent or misshaped when in use, such irregularity 50 will be compensated automatically.

55 In carrying out my invention I employ a

bail as heretofore, but the rod which carries the pressure rolls is mounted in bearings which permit the rod to move vertically or radially towards and from the platen and yielding devices, such as coiled springs, are 60 arranged in the bearings and exert pressure on the opposite ends of the rod tending at all times to press the rolls toward the platen. These springs operate automatically.

In the accompanying drawings I have 65 shown fragmentary views of parts of a typewriting machine embodying my improvements.

Figure 1 is a sectional view with parts in 70 elevation, showing how my improvements are applied to the bail which carries the upper pressure rolls.

Figure 2 is a detail view of some of the parts shown in Figure 1.

Figure 3 is a view similar to Figure 1 75 showing a slight modification.

Figure 4 is a detail view of some of the parts shown in Figure 3.

Figure 5 is a view similar to Figures 1 80 and 2 showing another modification and

Figure 6 is a detail view of parts of the mechanism shown in Figure 5.

Parts of a typewriting machine carriage frame are indicated at A, and B indicates a 85 platen. C indicates a shift rail and D a ball bearing interposed between the shift rail and the carriage rail E which has a flange or lip e overhanging the bearing. The paper table is indicated at F and G indicates the paper pan or guide beneath the platen. The bail is indicated at H and as heretofore comprises side arms or members K which are 90 pivoted to the carriage frame at k. A spring L is connected with the side arm K at l and with the carriage frame at l'. This spring 95 is so disposed and so connected with the carriage frame and with the bail that when the bail is in working position it pulls the pressure rolls R with a yielding pressure upon the platen. When the bail is raised or 100 swung backwards on its pivots, the spring L holds the bail in its raised position. The springs L are employed on opposite sides of the machine. The rod M which carries the pressure rolls R is provided with a scale as 105 indicated at r and the rolls R as heretofore are adapted to rotate about the axis of the rod and also to slide longitudinally thereon.

In Figure 1 the front end of the arm K is provided with a vertical slot N in which 110

one end of the rod M is mounted as indicated in Figure 2. The end of the rod shown in Figure 2 is provided with a handle O which provides a convenient way of raising 5 the bail. In the slot N above the rod M is inserted a spring S which is a compression spring and tends to move the rod downwardly in the slot. Both ends of the bar M are mounted in the manner indicated in Figures 1 and 2. The rolls R may be adjusted 10 in the usual way. They rotate about the axis of the rod M as heretofore and normally they bear with equal pressure upon the top of the platen, but it is obvious that should 15 the bail or some of the members thereof become twisted or bent or should the pivot bearings of the bail be changed from their normal position, the rolls R on opposite sides of the machine would not bear with equal 20 pressure on the platen, but by employing the spring bearings for the rod M this contingency is met, because if the rod M is moved out of its parallel relation with the platen so that the roll on one side of the 25 machine is slightly raised from the platen, the spring S on this side of the platen will move it back to its proper position. The two springs S on opposite sides of the machine serve to automatically keep the rolls 30 R in contact with the platen when in working position and preserve a uniform pressure of the rolls on the platen.

The construction shown in Figures 3 and 4 is substantially the same as that shown in Figures 1 and 2 except that in this case the front ends of the bail arms are shaped somewhat differently, the slots N being inclined upwardly and forwardly and pull springs S' are employed, the front end of each 40 spring being connected with the rod M and the rear end of each spring being connected at s to a stop lug P on the bail arm K.

In Figure 5 the construction is somewhat similar to that shown in Figure 1, but in 45 this case the slot N is inclined forwardly in the manner indicated in Figure 3, and the spring S which is similar to that shown in Figure 1 is arranged in this slot. In other respects the construction is the same as that 50 heretofore described.

As indicated in Figure 6 the upper end of the spring may be made to bear against a lug n extending laterally from the arm K.

While I have shown the arm K as being 55 formed with guide slots, other forms of guides may be employed.

The relation of the pivots of the bail arms and the points of contact of the rolls on the platen is of practical importance. That 60 shown is found to be most efficient.

I claim as my invention:

1. In a typewriting machine, the combina-

tion with the platen of upper pressure rolls, a rod on which the rolls are mounted, arms pivoted in rear of the platen and having 65 elongated guides in their front ends in which the ends of the rod are mounted, and devices acting upon the rod for yieldingly moving said rod with the rolls towards the platen.

2. In a typewriting machine, the combination with the platen of upper pressure rolls, a rod on which the rolls are mounted, arms pivoted in rear of the platen and having 70 elongated slots in their front ends in which the ends of the rod are mounted, and devices acting upon the rod for yieldingly moving the rod with the rolls towards the platen.

3. In a typewriting machine, the combination with the platen of a set of upper 80 pressure rolls mounted in a support movable towards and from the platen, and yielding devices in said support for moving the pressure rolls in their support toward the platen.

4. In a typewriting machine, the combination with the platen of arms pivoted in rear of the platen, a set of pressure rolls mounted in said arms, and yielding devices at the 90 front end of said arms for moving the pressure rolls in their support toward the platen.

5. In a typewriting machine, the combination with the platen of a swinging frame having elongated guides in its front end 95 above the platen, a rod carrying pressure rolls having its ends mounted in said guides, and a spring at the front end of each arm engaging the roll carrying rod and tending to move said rod with the rolls toward the platen.

6. In a typewriting machine, the combination with the platen of a roll supporting rod, a set of upper pressure rolls on said rod, a support for the rod movable towards and from the platen about an axis in rear of the platen, a spring for holding the support in normal working position, and springs at the front end of the support operating upon the roll supporting rod to move the rod and the rolls toward the platen.

7. In a typewriting machine, the combination with the platen of upper pressure rolls, a rod on which the rolls are mounted, arms pivoted in rear of the platen and having 115 elongated guides in their front ends in which the ends of the rod are mounted, lugs extending laterally from the front ends of the arms, and springs engaging said lugs and said rod for yieldingly moving the rod with the rolls towards the platen.

In testimony whereof, I have hereunto 120 subscribed my name.

EDWARD B. HESS.
